COMBINED CARTRIDGE BELT AND GAME CARRIER

Eugene H. Wicker, 3322 S. 9th, and Walter J. Orzel,
2018 Pestalozzi, both of St. Louis, Mo.

Filed Aug. 14, 1961, Ser. No. 66,336

Term of patent 14 years

(Cl. D3—10)

We claim:

The ornamental design for a combined cartridge belt and game carrier, as shown.
